UNITED STATES PATENT OFFICE.

JUDSON W. WARNER, OF ONEIDA, NEW YORK.

BOILER-FURNACE.

SPECIFICATION forming part of Letters Patent No. 508,790, dated November 14, 1893.

Application filed March 7, 1893. Serial No. 464,974. (No model.)

To all whom it may concern:

Be it known that I, JUDSON W. WARNER, of Oneida, in the county of Madison and State of New York, have invented certain new and useful Improvements in Boiler-Furnaces; and I do hereby declare that the following is a full, clear, and exact description thereof, reference being had to the accompanying drawings, and to the letters and figures of reference marked thereon, which form part of this specification.

The present invention is a sectional boiler especially designed for heating purposes, and is an improvement upon the boiler for which I was granted Letters Patent on the 8th day of September, 1891, No. 459,243; and it has special reference to the construction of the boiler sections whereby furnaces of different heating capacities can be readily formed, either with a surface fuel feed, or a reservoir fuel feed or if desired with double fire boxes, and either, or both surface and reservoir feeds.

Another object of the invention is to produce a circulation of water through the grate so as to keep down the temperature of the latter and thereby protect it from the destructive action of the burning fuel.

The invention therefore consists in the novel construction of the boiler sections; in the novel arrangement of the water circulating pipes in the grate; and in the novel construction and combinations of parts hereinafter fully described and claimed.

In the accompanying drawings: Figure 1 is a perspective view, partly broken, of my improved sectional boiler. Fig. 2 is a longitudinal central vertical section, and part side elevation of the boiler. Fig. 3 is a face view of one of the "reservoir" sections, and Fig. 4 a face view of the opposite reservoir section; said Figs. 3 and 4 showing the "meeting faces" of said sections. Fig. 5 is a face view of an intermediate section. Fig. 6 is a view of the rear section. Fig. 7 is a face view of the fire box dividing section. Fig. 8 is a detail.

As shown in Figs. 1 and 2 the boiler has two fire boxes, one of which is supplied with fuel by hand as in ordinary surface burning furnaces; and the other is supplied with fuel from a reservoir as in self-feeding furnaces. The fire boxes are situated one behind the other, so that the heated products of combus-

tion generated in the first fire box pass through the flues of the second fire box on their way to the chimney, and hence in moderate weather it is only necessary to employ one fire to heat 55 the entire boiler.

It will be perfectly feasible in the double heater to make both fire boxes surface burners, or provide both with fuel reservoirs, as the furnace is made up of sections which may 60 be increased in number, and arranged as desired. I have shown in the drawings one arrangement forming a very satisfactory boiler for heating large buildings. I have further provided numerous brush openings in the sections, and between the sections, so that the entire system of flues can be readily cleaned without anyone having to crawl into the boiler, and without taking the sections apart, and some of these brush openings or passages 70 perform a most important office in assisting in establishing a thorough circulation of heated products upward between and around the water legs, and in a natural course from the fire to the smoke flue, without diminishing 75 the surface exposed to the radiated heat of the fire, and increasing the water heating surface in direct contact with the products of combustion. I will now describe the boiler in detail, referring to similar parts by similar letters and numerals of reference.

The boiler as shown is composed of a front section A, then five similar sections B, then an intermediate section C dividing the two fire boxes, then another section B, then two 85 fuel reservoir sections D, E, followed by another section B, and a rear section F. Twelve sections in all.

Section A consists of two vertical hollow water legs A' A' connected at top by a transverse water holding limb or portion A² below which is another transverse water holding limb A³, the opening between said limbs and the legs being closed by a door a by which access can be had to the flues.

Intermediate limb A³ and the bottom of the sections is a transverse hollow limb A⁴ which forms the front wall of the fire chamber 1. The opening between limbs A³, A⁴, and legs A' is closed by a door a' through which access can be had to the fire chamber 1. The bottom of the water legs may be connected

by a transverse hollow limb A^5 , and the opening between the limbs A^4 , A^5 , and legs A' may be closed by a door a^2 through which access can be had to the ash pit. The front section 5 may have lateral flanges A^6 on its sides through which pass the section uniting bolts hereinafter referred to. Through the limbs A^2 , A^3 , are made transverse brush openings A^7 which are produced by casting or otherwise forming transverse tubes in the limbs open at both ends as shown. The outer ends 10 of said brush openings are closed by caps or covers a^4 as shown.

Each section B consists of two vertical water legs B' connected at top by a tubular limb B^2 below which is another limb B^3 , and below this (about center of legs B') is another limb B^4 which latter is, as shown, deeper than either of the other limbs so as to have the 15 most water surface in that part of the section exposed to the fiercest heat. The limbs B' may also be connected at bottom by a transverse limb B^5 . The limbs B^2 , B^3 may be directly connected at center by a vertical hollow tube 20 B^6 , and limbs B^3 , B^4 , by a similar tube B^7 . By this means a most thorough circulation of water is provided, and a large water heating surface exposed to the heated products of combustion.

Through each limb B^2 , B^3 , B^4 , are formed brush openings b similar to those in section A and formed relatively thereto so that when a section or sections B are set up with sections A, the brush openings correspond in the 30 several sections, and form direct passages longitudinally through the boiler. Access to the brush openings in limbs B^3 is had through door a of section A.

The section C is constructed like sections 40 B with but one difference, which is, that instead of having supports for a grate as do sections B, it has an additional transverse limb C' which ousts the grate bar and forms a bridge wall or back or fire chamber 1 as shown 45 in Fig. 2. Like parts and features of sections B and C are similarly lettered.

The grate sections D, E, are constructed with legs and limbs like sections B, but in the meeting faces of sections D, E, which are always to be placed together, is formed the coal 50 reservoir or feeder, half in each section. The opposed faces of the sections D, E, as shown in Figs. 3 and 4 have a curved shallow channel D' E' respectively formed in them. The front and back walls d , e , of this channel extend between limbs B^4 , B^3 , and B^3 , B^2 , and are hollow as shown, the lower end of the channel terminating at the lower edge and centrally of limb B^4 , and at the upper end of the channel 60 terminating at the side of the section and at end of limb B^2 . The walls d , e , also form part of the walls of the limbs B^4 , B^3 , B^2 , which are narrowed by said channel. The top and bottom or opposite side walls d' e' d^2 , e^2 , of 65 this channel in the respective sections are so formed that when the sections D, E, are put together, a close continuous passage or fuel

reservoir or feeder is produced between said sections as shown. The upper end of said reservoir is closed by a door D^3 in the side of the 70 complete boiler as shown. This construction enables the reservoir to be more readily filled than if it were on top of the boiler. The brush openings may extend through the front and back walls of the reservoir section if desired. 75

A damper E^3 is located in the upper part of the reservoir and can be adjusted by a damper rod E^4 as indicated in the drawings, so that before the door can be opened the 80 damper rod has to be thrown back which opens the damper inside and allows the gas which has accumulated in the top of the coal to pass off into the flue, which otherwise would ignite and explode on opening the door. The 85 rear section F corresponds in contour with the other sections and has an opening F' for the escape of the products of combustion near its top about opposite the flues between limbs 90 B^2 , B^3 , then it has another opening F^2 below the level of limb B^4 closed by a suitable door through which access can be had to the fire chamber, and below this another opening F^3 closed by a suitable door through which access can be had to the ash pit. The section 95 is hollow and water can circulate therethrough substantially as in the front section. It may also be formed with brush openings if desired.

As shown in Fig. 2 a second fire chamber 2 is formed between section C and rear section 100 F by the intermediate sections B, D, E, B, and access is had thereto through opening F^2 in the rear section, and to the ash pit thereunder through opening F^3 . It will be noticed that the limbs of the intermediate sections 105 are somewhat oval shaped, being wider at top so that when the sections are assembled together the limbs touch at the top thus forming closed transverse spaces or pockets 3 in the top of the fire chamber, and in the longitudinal flues 4, 5, formed between the series of limbs B^4 , B^3 , and B^3 , B^2 , as shown. These 110 pockets serve to trap the heat, but it is not confined therein, simply retarded, as the openings b , b , form short connecting flues between 115 the pockets so that the heat circulates up into the pockets and then along through openings b between the pockets to the ends of the flue as indicated by the tailless arrows in Fig. 2, 120 while the heavier currents proceed through the main flues as indicated by the ordinary arrows in said figure. By this inter-circulation between the pockets the heat is induced to ascend thereinto and clogging thereof by 125 deposits of dust and soot is retarded and the limbs and pockets are subject to both direct and radiant heat, but if openings b were omitted and the pockets closed at top, only radiant heat would enter therein.

The sections have lateral perforated ears G 130 on their sides through which pass bolts g , g , uniting adjoining sections as indicated in the drawings. The bolts may pass through the side flanges of the front section and through

the rear section as indicated in the drawings. It will be seen that by this fastening any number of the sections may be united in any order desired. The several sections are formed 5 on their opposed faces respectively, near their outer edges with grooves and tongues as indicated at H, H, Fig. 2 so that a close joint can be made between the sections from the outside. Lateral transverse recesses I, I, are 10 made in the opposed faces of adjoining sections, and when the sections are secured together these recesses form brush openings in the side of the boiler through which access can be had to the pockets above the fire chamber for cleansing them. These openings are 15 closed by suitable doors L' which may be secured to frames L² bolted on the sections as indicated in the drawings.

I', I', designate water pipes extending 20 transversely through the grate supporting sections, and lying just beneath and in contact with the grate and forming part thereof. In practice I propose to mount the grate pieces 25 on these pipes, but this particular feature forms the subject matter of another application for patent filed by me on the 9th day of March, 1893, Serial No. 465,297, and is therefore not herein specifically claimed. Each 30 pipe I' is preferably connected at one end by a suitable joint D higher than the grate to the section by which it is supported, and at the other end to the opposite side of the section, or it may be connected by a pipe i to the front or rear section as shown in Figs. 1 35 and 2 which is below the grate. By this means a more direct and powerful circulation of water through the pipes is produced, and the temperature of the grate is reduced and utilized to raise the temperature of the water. 40 Each section is connected at bottom to a drum J by suitable couplings j, and at top to a drum K by couplings k. If desired each section, or any set of sections, may be directly connected to a radiator, so that different and independent 45 water circuits are established from and to the boiler through different or independent boiler sections, and those sections subjected to greatest heat made to serve radiators farthest from the boiler. It will be of course 50 obvious that sections C, D, E, may be omitted when it is desired to make only a surface burning boiler. Or that section C may be omitted, or sections D, E, transposed to the central portion of the boiler when it is desired 55 to have a self feeding boiler, and that the length and capacity of the boiler may be governed by the number of sections used in it.

It will be seen that each and every section 60 extends from the top down to the very bottom of boiler, forming as it does, a sectional base, which feature is new and very essential, as it often happens after a boiler has been set up, it is found too small, or for some reason it is necessary to increase the size, which in my 65 boiler can be done by simply removing the front or back section and adding as many more as may be necessary.

Having described my invention, what I claim as new, and desire to secure by Letters Patent thereon, is—

1. In a sectional boiler, the combination with the front, rear and intermediate water holding sections, of a series of independent water-circulating pipes extending between fire-chamber and ash pit and connected by 75 one end to an intermediate section, and by the other end to the front or rear section, substantially as set forth.

2. In a sectional boiler, the combination with a water holding section, having vertical 80 water holding legs and transverse water-holding limbs, and constituting part of the fire-chamber and flue passages of a separate water-circulating pipe extending transversely between and entirely through the legs of the 85 section, below and adapted to sustain a grate piece, substantially as described.

3. In a sectional boiler the combination of the front, rear, and intermediate sections, and the sections D, E, having legs B' and transverse limbs B², B³, B⁴, and coal reservoir 90 partly formed in the opposed faces of said sections, opening at the side of the boiler, and the water-drum at top of the boiler substantially as specified.

4. In a boiler having horizontal return flue passages, the combination of the hollow front and rear sections and hollow intermediate sections, constructed substantially as described so that each forms and contains part of the 100 base, ash-pit, fire chamber and upper and lower flue passages of the boiler and supports part of the grate; and a grate piece mounted on each of said intermediate sections; between the ash-pit and fire-chamber portions 105 thereof; with another intermediate section similar to the others but having the grate piece replaced by an integral hollow water-circulating limb, whereby two fire-chambers are formed in the boiler, substantially as set 110 forth.

5. In a return flue boiler, the combination of the transverse sections forming part of the ash-pit, fire chamber, and having transverse water-holding limbs above the fire chamber, 115 and pockets intermediate said limbs; and lateral recesses in the meeting faces of the sections forming openings in the sides of the boiler at the ends of said pockets for cleaning them, substantially as specified.

6. In a return flue boiler furnace, the combination of the separate sections each forming part of the ash-pit and fire-chamber and having transverse water-holding limbs above 125 the fire chamber, and pockets intermediate said limbs; and recesses in the meeting faces of the sections forming lateral openings in the sides of the boiler at the ends of said pockets, and transverse openings through said limbs, substantially as set forth.

7. In a return flue sectional boiler, the combination of similar transverse water-holding sections each forming part of the base, ash-pit, fire-chamber, and flue-passages, and hav-

ing lateral recesses in their opposed meeting faces forming brush openings between the sections, substantially as described.

8. For a sectional boiler, the herein described water-holding section B, having vertical legs B', transverse limbs B², B³, B⁴, and brush openings b in said limbs, and lateral recesses in its sides at the ends of the lower limbs, substantially as set forth.

10. 9. For a sectional horizontal return flue boiler, the herein described water holding section C, having vertical legs B', transverse limbs B², B³, B⁴, and hollow transverse back C' below and separated from said limbs, constructed as shown.

15. 10. For a sectional boiler, the herein-described section C, having vertical legs B', transverse limbs B², B³, B⁴, hollow transverse water-back C' below said limbs, brush openings through said limbs, and lateral recesses in the legs adjoining the lower limbs, for the purpose specified.

11. In a sectional boiler the combination of the front section A, rear section F, intermediate sections B, and intermediate coal reservoir sections D, E, the water circulating pipes

supported in sections B, D, E, and extending therethrough communicating at their opposite ends with separate sections by connections exterior to the sections, and the supply and return pipes, all substantially as set forth.

30 12. The combination of the middle section C, the fuel feed reservoir sections D, E, having curved reservoir channels in their meeting faces at one side of the section C, the intermediate similar sections B, B, at each side of section C, and the outermost front and rear sections A and F, each section forming part of the base, ash-pit, fire chamber and flue passages, and all combined to form a horizontal return flue boiler, having two fire chambers, one of which is beneath the feed reservoir, 35 substantially as specified.

40 In testimony that I claim the foregoing as my own I affix my signature in presence of two witnesses.

JUDSON W. WARNER.
